UNITED STATES PATENT OFFICE.

LEWIS A. LEESER, OF BALTIMORE, MARYLAND.

TRUNK.

SPECIFICATION forming part of Letters Patent No. 323,434, dated August 4, 1885.

Application filed September 25, 1884. (No model.)

To all whom it may concern:

Be it known that I, LEWIS A. LEESER, a citizen of the United States, residing at Baltimore, in the State of Maryland, have invented 5 certain new and useful Improvements in Trunks, of which the following is a specification.

My invention relates to a certain improvement in trunks, whereby a trunk is strengthened and protected, as hereinafter first described, and then specifically claimed.

The accompanying drawings illustrate the invention.

Figure 1 is a view of the improved trunk. 15 Fig. 2 is a section view of a corner of the trunk.

The box A and lid B of the trunk, made of wood, may be constructed in any well-known or any desired manner. The wood strips C, 20 such as are usually attached on the outer surface, are employed; but instead of attaching them by nails, screws, or rivets, I place the wood strip against the box, and cover each wood strip with a piece of rawhide, d, and then make the rawhide fast to the box by a row of stitching, e, along the two edges of the wood strip. The rawhide, being thus placed 25 over the wood strip and sewed directly to and through the box, serves as a strong fastening for the wood strip. As each row of stitches e 30 is located in the inner angle, as seen in Fig. 2, between the edge of the wood strip and the surface of the box, the stitches are protected from damage or wear by the projecting edge 35 or outer angle, f.

Any suitable cord or thread may be used for stitching; or strips of rawhide may be used for this purpose.

The manner of strengthening the plain angles of the box and lid is shown in Fig. 2. 40 To strengthen, for instance, the angle formed by the front and one end of the box two wood strips are employed. The first strip, C, is placed against the box front A, so that one edge, h, is coincident with the edge of the said angle. The second wood strip, C', is placed

against the end of the box, so that one edge, i, is in contact with the first strip, as shown. The opposite edge of each strip forms an outer angle, f, and extends across—that is, up and 50 down—the front and end of the box. A covering, d', of rawhide or other material, as hereinafter described, is then placed over the said two strips C C' and made fast to the box by two rows of stitches, e, extending along the 55 edges of the strip, each row located in the inner part of one of the angles, f. In the same manner the other angles of the box are strengthened. Where the strips and covering material meet at the corners they are mitered, as 60 at k.

I have described, and I prefer to use, rawhide over the wood strips; but I may use other material—such as leather and cotton duck—and sew the same directly to the box or lid of 65 the trunk.

By the described construction of the corners the wood of the box or lid is prevented from splitting, since the guard-strips extend crosswise of the grain of the wood. 70

A trunk thus constructed is strong, of light weight, because the nails and iron straps are dispensed with, and neat in appearance.

Having described my invention, I claim and desire to secure by Letters Patent of the United 75 States—

A trunk whose box or lid is made of wood and provided at its angles or corners with two wood strips, C C', extending crosswise of the grain of the said box or lid, one strip being 80 placed against each surface at the angle or corner and secured by a covering of suitable material, as described, placed over the said two strips and made fast to the box, substantially as set forth. 85

In testimony whereof I affix my signature in presence of two witnesses.

LEWIS A. LEESER.
